UNITED STATES PATENT OFFICE.

ARMAND LYNNE PASCHALL, OF SPRINGFIELD, OHIO, ASSIGNOR TO THE BAUER BROS. COMPANY, OF SPRINGFIELD, OHIO, A CORPORATION OF OHIO.

GRINDING-MILL.

1,310,031.

Specification of Letters Patent. Patented July 15, 1919.

Application filed August 15, 1916. Serial No. 114,967.

To all whom it may concern:

Be it known that I, ARMAND LYNNE PASCHALL, a citizen of the United States, residing at Springfield, in the county of Clark 5 and State of Ohio, have invented certain new and useful Improvements in Grinding Mills, of which the following is a specification.

This invention relates to improvements in 10 grinding mills and more particularly to that type known as attrition mills in which vertically arranged grinding disks are employed having longitudinally arranged driving shafts.

15 One of the objects of the invention is to provide improvements in the arrangement for causing the separation of the grinding disks under certain conditions such as the entrance of foreign substances between the 20 same.

A further object of the invention is to provide means for relieving and utilizing the air pressure in the grinding casing, due 25 to the revolving action of the grinding disks, to secure a more effective feed of the material to be ground.

In the accompanying drawings:

Figure 1 is a longitudinal section of a machine embodying my improvements.

30 Fig. 2 is a transverse section of a portion of the same.

Fig. 3 is a section on the line 3—3 of Fig. 2.

Fig. 4 is a top plan of a portion of the 35 same.

Fig. 5 is a detail section.

In mills of this character it has been common to make provision for the separation of the grinding disks to obviate the danger of 40 breakage by the entrance into the mill of hard foreign substances, this separation being accomplished by a longitudinal movement of one of the driving shafts and its disk. In certain types of mills it was usual 45 to provide positive means for throwing the movable shaft and its disk into the proper grinding position and to rely upon a spring for moving the shaft and disk in the opposite direction. It was also usual in that type of 50 mill to provide other springs for yieldingly holding the movable disk in grinding relation with the stationary disk so that the disks could automatically separate under certain conditions; the tension of these latter 55 springs being of course in the opposite

direction and against the tension of the first mentioned spring. This has resulted in making it necessary to have the first mentioned spring of a comparatively light character so that it could not at all times be relied upon to quickly separate the disks, as it was found that the driving action of the belt upon the pulley of the movable shaft would tend to counteract the tension of this spring and prevent its quick and effective 60 action. In order to overcome this difficulty I have provided means for shifting the movable shaft and its disk positively and in either direction when it is desired to accomplish this by what is called the quick release 65 devices, but at the same time provide for yieldingly holding the shaft and disk in proper driving relation by springs which will permit their automatic separation.

The grinding disks are of the usual form, 70 represented by 1 and 2. The grinding disk 1 is connected with the shaft 3, which is mounted in suitable bearings on the base 4 and this shaft and its grinding disk are immovable longitudinally. The other disk 2 75 is connected with the shaft 5, the inner end of which is supported in the bearings 6 of the bearing block 7 and the outer end of which is supported in bearings in the box 8. The bearings employed in the different boxes are 80 of the ball type, it being necessary to describe only those in the box 8 in order to illustrate the improvements which I have made. The shaft 5 is reduced at its extreme outer end and between the shoulder formed 85 by the reduction and the nut 9 is a race 10. Fitted in the box 8 is the co-acting race 11, ball bearing 11^a being placed between the two races in the usual way. Slidably mounted in the box 8 is a head or block 12 90 to which is swivelly connected a screw 13 which projects loosely through the end of the bearing box and is threaded in a cross-bar 14, slidably mounted on the stationary pins 15 which project from the end of the 95 box; a jam nut 14' being employed to keep the screw from turning in the bar after the proper adjustments have been made. Pivots connected to each end of the cross-bar 14 is a link 16, the opposite ends of the links being in turn pivotally connected to projecting arms 17 of a bifurcated lever 18, the respective parts of which are pivotally connected with sleeves 19 slidably arranged on rods 20 which are clamped to laterally ex- 100

tending lugs or ears 21 projecting from the sides of the bearing box 8 and project rearwardly therefrom. Between the sleeves 19 and collars 22, held in position by nuts 22, 5 are interposed coil springs 23. It is these springs 23 which hold the grinding disks in grinding relation with each other. When the parts are in the position shown in Fig. 4, it will be seen that the links 16 and arms 10 17 are in longitudinal alinement with each other so that the springs will tend to hold the cross-bar 14 toward the center of the machine, the movement being limited, however, by the contact of the sliding sleeves 19 15 with the ears 21 or interposed collars 24. When the disk 2 is caused to separate from the disk 1 and its shaft 5 forced longitudinally, it is against the tension of these springs 23, and if desired a quick release 20 may be accomplished by throwing the bifurcated lever away from the center of the machine so as to cause the arms 17 to push the links 16 and hence the cross-bar 14, screw 13 and block 12 away from the center of the 25 machine.

As before mentioned, it was the former practice to employ a spring to assist in the separation of the disks, and formerly this spring was inserted between the inner end 30 of the bearing box 8 and the ring 25. In the present construction, however in which this spring is dispensed with, I have provided gibs 26 arranged in slots 27 in the walls of the box 8 and embracing the head 22 and 35 ring 25 so as to connect them together, as a result of which, when the head 12 is pulled by the operation previously described, the bearings, ring 25, shaft 5 and disk 2 will all move positively together. Two of these gibs 40 are preferably employed, arranged diametrically opposite each other and when the parts are removed from the box 8 the gibs are readily removable so as to permit the separation of the parts of the bearing.

45 In order to prevent the head 12 and ring 25 from turning, I provide the head 12 with small projecting ribs 12^a and provide the ring 25 with similar ribs 25^a, which ribs fit in recesses formed in the respective ends of 50 each of the gibs 26 and thus lock the head and ring to the gibs so far as rotary movement is concerned.

In the operating of grinding, a pressure

of air will accumulate in the casing 28 due to the revolving action of the grinding disks 55 and this pressure of air will materially interfere with the proper feed of the material from the spout 29, which material, it will be understood, finds its way through the openings 30 about the hub of the disk 1. In 60 order to overcome this difficulty and to utilize the air pressure to assist in the feeding operation, I have provided an opening or passageway 31 leading from the upper part of the casing 28 to a point in the hopper 29 65 above the point of discharge therefrom. The result of this arrangement is that the air, instead of accumulating and forming a pressure in the casing 28 will circulate through the same and into the spout 29 70 through the passageway 31 and thence back into the casing through the openings 30, thereby materially assisting in the feed of the material. The wall of the spout overlies the opening 31, as indicated at 29^a, so as to 75 tend to deflect the air downwardly.

Having thus described my invention, I claim:

1. In an attrition mill, a casing, a revolvable grinding member in said casing, a chute to receive the material to be ground and discharge the same by gravity near the axis of said grinding member and a passage way from said casing having opposite vertical walls providing a downward discharge 85 into said chute whereby the material to be ground will fall free of the discharge opening of said passageway and be assisted in its fall by the pressure from said opening.

2. In an attrition mill, a casing, revolvable 90 grinding members in said casing, a chute to receive the material to be ground and discharge the same by gravity near the axis of said grinding members and a passage way from said casing having a downward 95 discharge into said chute through a vertically disposed opening in a set off in the wall of said chute whereby the material to be ground will fall free of the discharge opening of said passage way and be assisted 100 in its fall by the pressure from said opening.

In testimony whereof, I have hereunto set my hand this 11th day of August, 1916.

ARMAND LYNNE PASCHALL.
